UNITED STATES PATENT OFFICE.

WILLIAM P. HAMMOND, OF MAPLEWOOD, NEW JERSEY.

DESIGN FOR A COMBINED MIRRORSCOPE AND PARKING-LIGHT.

58,228.

Specification for Design.

Patented June 28, 1921.

Application filed April 1, 1921. Serial No. 457,830. Term of patent 14 years.

To all whom it may concern:

Be it known that I, WILLIAM P. HAMMOND, a citizen of the United States, residing in Maplewood, in the county of Orange and State of New Jersey, have invented a new, original, and ornamental Design for a Combined Mirrorscope and Parking-Light, of which the following is a specification, reference being had to the accompanying drawing, forming a part thereof.

Figure 1 is a view in front elevation of a combined mirrorscope and parking light, showing my new design.

Fig. 2 is a rear view, slightly in side elevation of same.

The combined mirror and parking light illustrated is provided with a transparent

plate, having a mirrored surface covering a centrally located zone thereof, and a ring-like outer colored zone, preferably red, forming a danger signal when illuminated. This transparent plate is supported in a casing, said casing being of curved shell-like formation, said curve approximating an ogee curve, terminating in a centrally located protuberance, apertured to receive a bull's eye crystal of uncolored glass, as shown more particularly in Fig. 2.

I claim—

The ornamental design for a combined mirrorscope and parking light, as shown and described.

WILLIAM P. HAMMOND.
